UNITED STATES PATENT OFFICE.

GEORGE M. VOLTZ AND CHARLES H. SHULTZ, OF ST. JOSEPH, MISSOURI.

OVEN FOR VAPOR-STOVES.

SPECIFICATION forming part of Letters Patent No. 399,301, dated March 12, 1889.

Application filed April 20, 1888. Serial No. 271,292. (No model.)

To all whom it may concern:

Be it known that we, GEORGE M. VOLTZ and CHARLES H. SHULTZ, citizens of the United States, residing at St. Joseph, in the 5 county of Buchanan and State of Missouri, have invented new and useful Improvements in Ovens for Vapor-Stoves, of which the following is a specification.

Our invention relates to an improvement in 10 ovens for vapor-stoves; and it consists in the peculiar construction and combination of devices, that will be more fully set forth hereinafter and particularly pointed out in the claims.

15 In the accompanying drawings, Figure 1 is a perspective view of an oven embodying our improvements, the door of the same being open. Fig. 2 is a vertical longitudinal sectional view of the same, showing the valves or 20 dampers closed. Fig. 3 is a similar view showing the valves or dampers open. Fig. 4 is a perspective view, partly in section, illustrating a modification of the invention.

A represents the rectangular outer shell of 25 the oven, which is provided on one side with an opening, B, and has a hinged door, C, to close the said opening. In the ends of the shell A, near the upper side thereof, are made openings 30 D. On the upper side of the oven are secured handles E, by means of which the oven may be readily moved about. The bottom of the shell A has the large opening F, which is adapted to register with the holes in the vapor-stove when the oven is placed thereon.

35 G represents a bottom plate, which is supported upon horizontal cross-bars H, and extends from side to side of the shell A, at a suitable distance from the lower side thereof. The bottom plate, G, is made of sheet metal, 40 and its ends are bent to form flanges g. The length of the bottom plate, G, is such that a space is left between the ends of the same and the ends of shell A.

L represents the lining of the oven, which 45 is made of a single piece of sheet metal having its lower ends bent outwardly at right angles to form flanges M, which are adapted to fit under the flange g of the bottom plate, so as to secure the said lining thereto.

50 In order to insert the lining in the oven, it is bent to form a scroll or circle, and is intro-

duced into the oven through the doorway B. The lower ends of the lining are then forced outward, so as to cause their flanges M to lock under the flanges g of the bottom plate. The 55 length of the sheet of metal of which the lining is made is such that when the lining is located in the oven it is out of contact with the end walls and top of the oven, and the upperside of the lining is curved or arched, as shown. 60 This provides an uninterrupted flue, which extends entirely around the lining of the oven between the same and end walls and top of the oven. In the sides of the lining, near the top of the same, are openings I, which are slightly 65 below the level of the openings D in the ends of the shell.

K represents a pair of dampers or valves or deflectors, which are hinged to the ends of the shell A at a point slightly below the openings D. The length of the said valves or dampers is equal to the width of the oven, and the free edges of the said dampers or valves are adapted to come in engagement with the sides of the lining, as shown in Fig. 2, so as to 75 close the flues at points between the openings D and I. The said dampers or valves are also adapted to be opened and swung against the sides of the lining so as to cover the openings I.

The operation of our invention is as follows: 80 The heat and products of combustion pass upwardly between the linings of the oven and the end walls thereof, and when the dampers or valves are open, as shown in Fig. 3, escape through the openings D into the outer air 85 and only serve to heat the oven to a minimum degree. When the said dampers or flues are closed, as shown in Fig. 2, the heat and products of combustion pass upward in the flues, strike against the lower sides of said 90 dampers or flues, and are deflected inwardly by the same and caused to enter the interior of the lining through the openings I. The said heat and products then escape into the upper portion of the oven or shell through 95 openings I' in the top of the lining, and from thence pass outward through the openings D. When the dampers are thus arranged, the oven will be heated to a maximum degree and caused to brown cakes, pies, or bread on both 100 sides at once.

In Fig. 4 of the accompanying drawings we

have illustrated a modification of the invention in which we constructed the oven with an inclined rigid deflector, K', that is placed above the openings I. The inclined deflector 5 K' may be secured either to the outer shell, A, or to the lining L, or to both, and it is designed to perform the function of a closed damper, and it directs the heat through the openings I into the oven and causes it to pass out through 10 the openings I' in the top of the lining L to the openings D, when the damper K, situated on the opposite side of the oven, is closed. When the damper K is open, the heat passes along that side of the oven and then out 15 through the openings D, heating the oven to a minimum degree and browning the articles in the oven on the bottom.

From the foregoing description and the accompanying drawings the construction, operation, and advantages of the present invention will readily be understood; and it is obvious that the passage of the heat may be regulated and controlled, and the pies, cakes, and the like be browned on the top and the 25 bottom at will, which is a great desideratum.

Having thus described our invention, we claim—

1. An oven for vapor-stoves having the outer shell provided with openings D, the lining L, arranged within the outer shell and forming an intermediate space between it and the outer shell, and having openings I in its side and openings I' in its top, and deflectors 30

adapted to open and close the intermediate space upon each side of the said lining L and 35 cause the heat to pass into the oven through the side or around and over the top of the oven, substantially as described.

2. A portable oven having the shell A, provided with openings D, the lining arranged 40 within the shell and having the openings I in its sides and the openings I' in its top, and the deflectors hinged to the lining and adapted to open or close the intermediate space, and also the openings I, to cause the heat either 45 to pass through said openings I or to pass around the top of the oven, substantially as described.

3. A portable oven having the shell A, provided with the openings D, the lining L, arranged within the oven and having the openings I in its sides and the openings I' in its top, and inclined deflectors arranged in the spaces between the walls of the shell and the sides of the lining, having their upper edges 50 55 above the openings I, substantially as described.

In testimony that we claim the foregoing as our own we have hereto affixed our signatures in presence of two witnesses.

GEORGE M. VOLTZ.
CHARLES H. SHULTZ.
